UNITED STATES PATENT OFFICE.

CHARLES W. LOCKE, OF LOWELL, MASSACHUSETTS, ASSIGNOR TO THE
AMERICAN MASON SAFETY TREAD COMPANY, OF SACO, MAINE.

TREAD FOR STAIRS, &c.

SPECIFICATION forming part of Letters Patent No. 605,732, dated June 14, 1898.
Application filed June 1, 1897. Serial No. 638,887. (No model.)

To all whom it may concern:

Be it known that I, CHARLES W. LOCKE, of Lowell, in the county of Middlesex and State of Massachusetts, have invented certain new and useful Improvements in Treads for Stairs, &c., of which the following is a specification.

My invention relates to the novel manufacture of treads for stairs, sidewalk-plates, walk-lights, coal-hole covers, carriage-steps, stirrups, and other places where it is desirable to have a non-slipperable surface.

The object of this invention is to produce a surface which is non-slipperable, so that a person stepping or walking thereon cannot slip and fall.

In the accompanying drawings, which illustrate a construction embodying my invention, Figure 1 is a plan view of a tread adapted for use with steps. Fig. 2 is a cross-sectional view on the line X-X, Fig. 1, looking in the direction indicated by the arrow. Fig. 3 is a detail reversed plan view of a portion of a plate. Fig. 4 is a detail sectional view hereinafter described.

Like letters of reference refer to like parts throughout the several views.

The plate A is of hard metal and may be produced by rolling, punching, drawing, forging, or any other desirable method, and preferably is made of mild steel, which forms the wearing-surface, and is provided with a nose B, which fits over the edge of the step. This plate A is provided longitudinally and transversely on its upper surface with grooves C and D, respectively, and each section of the plate between said grooves is provided with a hole E, which is filled with a soft non-slipperable material E', as lead, which may be placed in said holes by pouring or rolling. The under side of the plate A is provided at certain places with extensions F, which form a part, preferably, of the plate A, and these metal extensions bear upon the step or other place where the tread is being placed, and the hole F' extends through said metal extensions, and by means of screws the plate is firmly secured to the step or other place. The holes F' where these extensions F are located are not filled with the non-slipperable material, but are

left for the passage of the screws. In the 50 grooves C and D the dirt from the shoes is deposited away from the top of the plate.

It is obvious that the foot striking the soft non-slipperable material E' prevents slipping and falling, and thus there is produced a non-slipperable surface adapted for various uses. The holes E, in which the lead is placed, may be straight or tapering or of any shape, size, or arrangement desired.

When the plate above described is placed 60 upon the step, the said step forms a backing for said plate, and the lead poured or rolled into the holes E spreads out under the plate A in the space between said plate and the top of the step, and said lead is confined under 65 said plate by the nose B and side lugs A' and by the back of the step, so that a reservoir is formed under the plate A between the top of the step and said plate, and as said space is filled up the lead fills all the holes E, and by 70 this arrangement it is obvious that the lead E' in the holes E cannot be separated from the plate A and is held securely within said holes.

Instead of using the top of the step for a 75 back to the plate A another plate G' may be placed under said plate A, as shown in Fig. 4, and secured to the plate A and the step by screws G'. When the lead is poured or rolled into the holes E, it spreads out in the space 80 between the plate G' and the plate A and forms a reservoir G, and when said reservoir is filled the lead which is being poured in fills up all the holes E.

If the entire bottom of the plate A is in close 85 contact with the top of the step, so that no body of lead can be formed underneath, in a manner as above described, then pieces of metal may be cast across the holes E of the plate A and thus hold the soft material in 90 place.

I do not limit myself to the arrangement and construction shown, as the same may be varied without departing from the spirit of 95 my invention.

Having thus ascertained the nature of my invention and set forth a construction embodying the same, what I claim as new, and

desire to secure by Letters Patent of the United States, is—

1. A tread for stairs and other purposes consisting of a plate of hard metal provided with holes extending through said metal and tapering upwardly in combination with a soft material placed in said holes to produce a non-slippable surface, and grooves around each hole.
- 10 2. A tread for stairs and other purposes, consisting of a plate of hard metal provided with holes in combination with a soft material placed in said holes to produce a non-slippable surface, and means for holding a body of lead on the under side of said plate.
- 15 3. A tread for stairs and other purposes consisting of a plate of hard metal provided with holes extending through said metal and tapering upwardly in combination with a soft material placed in said holes to produce a non-slippable surface, means for holding said
- 20

soft material in place, and longitudinal and transverse grooves between said holes.

4. A tread for stairs and other purposes consisting of a plate of hard metal provided with holes extending through said metal and tapering upwardly in combination with a soft material placed in said holes to produce a non-slippable surface, means for holding said soft material in place, longitudinal and transverse grooves between said holes, and means for holding a body of lead on the under side of said plate.

In testimony whereof I have signed my name to this specification, in the presence of two subscribing witnesses, this 27th day of May, A. D. 1897.

CHARLES W. LOCKE
